(57) **CLAIM**

The ornamental design for a vehicle waistline and fender vent, as shown and described.

DESCRIPTION

FIG. 1 is a front right perspective view of a vehicle waistline and fender vent according to the present invention.

FIG. 2 is a front view of the vehicle waistline and fender vent shown in FIG. 1; and, FIG. 3 is a top view thereof.

The broken lines showing a vehicle, illustrate environmental structure that forms no part of the claimed design. The broken lines on the fender vent depict portions of the article which form no part of the claimed design.
